DOOR-CLOSURE MECHANISM

Application filed July 2, 1927. Serial No. 203,035.

This invention relates to door closure mechanism and particularly to closures for elevator hatchway doors.

In certain building structures such, for instance, as garages considerable time can be saved in transporting cars to different floor levels by utilizing an elevator having two floors or decks. When such an elevator is used, it is desirable that means be provided for opening and closing the doors at the two levels served by the elevator simultaneously. Furthermore, it is desirable that the door control mechanism be so arranged that the doors cannot be opened unless the elevator is positioned at the floor levels at which the doors are located.

One of the objects of the invention is to provide simple and practical door opening mechanism and means for locking the door in closed position.

Another object of the invention is to provide door opening and closing mechanism so constructed and arranged that a plurality of doors can be simultaneously opened and closed.

Another object of the invention is to provide door opening and closing mechanism for operating doors on a plurality of floors simultaneously and so constructed and arranged that the control devices at all of the floors controlled or served by the doors must be actuated before any of the doors can be opened.

Another object of the invention is to provide door closure mechanism with locking means arranged for operation as the door moves to closed position and adapted to assist in moving the door to closed position.

Another object of the invention is to provide door closure mechanism with improved and efficient counterbalancing mechanism so arranged as to compensate for variation or stretching of the counterweight cable.

Another object of the invention is to provide locking mechanism for the doors so interconnected with the door operating motor and the circuits thereof that the locking mechanism will be automatically released as the motor starts.

Another object of the invention is to pro-

vide a rotating counterweight opposed to the load lifted by the motor to assist the motor in its operation.

Further objects of the invention will appear from the following specification taken in connection with the drawings, which form a part of this application, and in which

Fig. 1 is a sectional elevation illustrating a plurality of floor levels, doors for closing the door openings therein and mechanism for opening and closing the doors;

Fig. 2 is a sectional elevation taken at right angles to Fig. 1;

Fig. 3 is a diagrammatic view illustrating the electric circuits for controlling the operation of the door locks and door operating motor;

Fig. 4 is a front elevation of one of the doors and the counterweighting and locking means therefor;

Fig. 5 is an enlarged elevational view partly broken away showing the counterweight and a combined door moving device and lock controlled by the counterweight;

Fig. 6 is a detail sectional elevation showing the door guiding track or channel and adjacent parts;

Fig. 7 is a detail sectional elevation showing the door lock;

Fig. 8 is a detail sectional elevation showing a modified construction of spring support for the counterweights;

Fig. 9 is an elevational view showing a slightly different form of door moving and locking device from that illustrated in Fig. 5;

Fig. 10 is a horizontal section through the door illustrating a bumper secured to one face of the door; and

Fig. 11 is a sectional elevation illustrating the location of the sheaves for the counterweight cable.

The invention briefly described consists of a plurality of door closures for closing door openings on different floor levels and operating mechanism and control devices for the closures so constructed and arranged that a plurality of the closures can be opened and closed simultaneously. A counterweight is provided for each door so constructed that when the counterweight is lowered and the

door is unlocked, the door will be opened by the counterweight. The counterweights are controlled by a single cable having thereon a plurality of vertically spaced members adapted to engage the counterweights and cause the counterweights to be elevated when the cable is raised or permit the counterweights to be lowered when the cable is lowered. The doors are so arranged that when the counterweight is raised by the cable, the weight of the door will cause the door to close.

The counterweight control cable is raised and lowered by means of a crank so constructed and arranged that the rotation of the crank through 180° will cause the door to be raised or lowered as the case may be.

The motor for operating the crank is so controlled that when a two floor or double deck elevator is used, manually controlled switches for both floors must be closed before the motor circuit is closed and the motor will operate. Furthermore, the closing of the two manually controlled switches also effects the release of the door locks for the two doors to be opened.

Means is provided for moving the doors to their final closed position by the movement of the doors themselves as they approach the closed position or in conjunction with the counterweights so that the door locks will operate to secure the door in closed position. This means is automatically released by the upward movement of the counterweight and is automatically placed in operation by the downward movement of the counterweight.

A rotating counterweight is provided upon the same shaft or integral with the crank which by gravity assists in raising the counterweight control cable and thus assists the motor in its operation.

Various novel features are incorporated in the door closure construction, operating mechanism for the door closures and circuit control devices for the motor and door locks and these will be brought out in more detail in the following description.

Door closure construction

In Figs. 1 and 2 there are shown a plurality of floor levels A, B, C and D. Each of the floor levels has a hatchway door opening 20 adapted to be closed by a door which in the form of the invention shown comprises a pair of sections 21 and 22 hingedly connected at 23.

The lower section 21 preferably has a bumper beam 24 secured thereto in position to be disposed opposite the rear bumper on the car to prevent the car bumper from engaging the door and to insure the positioning of the car in such a location that the door will not engage the car when it is raised and lowered.

The door sections are provided at their lateral edges with rollers 25, 26 and 27 posi-

tioned in channel tracks or guide rails 29 and 30. The guide rails are provided with vertical positions 35 and intermediate portions 36 curved at 37 to lead the doors from the vertical portions 35 to horizontal portions 38.

In Figs. 1 and 2 the doors at the floor levels B and C are open and the door at floor level A is closed.

Each door is adapted to be opened by a counterweight 40 having a pair of brackets 41 and 42 on which are rotatably mounted sheaves 43 and 44. A counterweight cable 45 has one end secured as shown at 46 to a fixed support and the cable is passed under the sheave 44 upwardly over a sheave 50 and downwardly to a bracket or lug 51 secured to the lower end of one of the side edges of the lower door section 21. A fusible link 52 is preferably interposed between the lower end of the cable 45 and the lug or bracket 51.

Another counterweight cable 53 is also secured to a fixed support and passes under the sheave counterweight 43 upwardly over a sheave 55 across above the door and around a sheave 56 and downwardly to a bracket or lug 57 projecting laterally from the opposite edge of the door section 21. A fusible link 58 is interposed between the bracket or lug 57 and the lower end of the cable 53.

The counterweight 40 is of sufficient weight to raise the door sections to open position when the weight is free to fall and by reason of the counterweight cable connections above described, it will be clear that the counterweight will move only one-half the distance of movement of the door sections.

It will be clear from the showing in Fig. 2 that the door section 21 in its wide open position is in inclined position. Since there is comparatively little friction and comparatively little force required to move the section 22 along the horizontal portions of the guide rails when the counterweight 40 is lifted, the door sections will move of their own weight to closed position.

Operating mechanism for door closures

The operating mechanism for the door closures is particularly designed for use with a two floor or two deck elevator shown diagrammatically at E in Fig. 2. The operating mechanism is, therefore, so constructed and arranged that a plurality of doors can be opened or closed simultaneously and in Figs. 1 and 2, the doors at floors B and C are open and the door at floor A is closed. In order to open the doors, the door locks are released and the counterweights are permitted to fall, thus causing the doors to be raised.

The counterweights are controlled by a single cable 60 which in the form of the invention illustrated is secured at its upper end to a crank 61 and passes over a sheave 62 and downwardly through openings 63 in the floors

and through central openings 65 in the counterweights and between the sheaves 43 and 44. The cable 60 has secured thereto vertically spaced clamps 68 and a spring 69 is interposed between each clamp and a support or plate 70 adapted to engage and support the counterweight. The clamps, springs and supporting plates are so relatively arranged that when the crank 61 is moved in a clockwise direction in Fig. 1 through 180°, the counterweights of the open doors will be lifted a sufficient extent to permit the doors to close. When the crank is then rotated again in a clockwise direction through 180°, the cable 60 will be lowered, permitting the counterweights of the unlocked doors to fall, thus opening the doors.

Each of the springs 69 is preferably so proportioned that it will support, for example, twice the weight required to reverse the balance and close the door controlled thereby. If it is assumed that the spring is half compressed by the counterweight when the counterweight is supported thereby, between this half compression and the full compression, the spring has a range of movement during which the door will be operated to close when the clamp and cable is raised. If the clamps and springs on all the floors are adjusted within this range, all of the doors will be properly operated. In case the counterweight cables or cable 60 stretch, the doors will still be operative as long as the amount of stretch is within the range of the springs.

The springs 69 also provide cushions for the counterweights and relieve the lifting cable and lifting mechanism from shock.

Fig. 8 illustrates one manner of mounting the springs between the clamp 68 and the bearing plate or support 70. In this figure there is shown a pair of plates 71 and 72 having telescoping sleeves 73 and 73'. Springs 74 are interposed between the plates 71 and 72, being disposed in sockets formed on the inwardly facing surfaces of the plates. It will be evident that the springs 74 can be readily removed and replaced, if desired.

The crank 61 is mounted on shaft 75 supported in brackets 76. The shaft 75 has secured thereto a counterweight 64 which has its center of gravity in a line at right angles to the longitudinal axis of the crank. This counterweight may be made integral with the crank, and thus avoid strains on the shaft fastenings and torsional strains within the shaft 75.

Shaft 75 also has secured thereto a worm gear 78 driven by a worm 79 carried by a shaft 80 having secured to its other end a worm gear 81 which in turn is driven by a worm 82 carried by a shaft 83 driven by a motor 84. During each opening or closing movement of one or more doors, the crank 61 is moved through 180°. For instance, as above stated when the crank is moved through

180° from the position shown in Fig. 1, the counterweights of the open doors will be raised, thus permitting the doors to close. When the crank is moved through the other half revolution, the cable 60 will be lowered and the counterweights of the unlocked doors will be lowered and the doors opened.

The crank counterweight, by its weight assists the motor in raising the cable 60 and its load, thus making the load more uniform and permitting the use of a smaller motor. It is obvious that the crank could be set to operate on vertical centers, in which case, the rotating counterweight would be placed directly opposed to the crank.

In order to insure the movement of the doors to completely closed position, means is provided for assisting the closing movement of the doors when they approach closed position.

One form of mechanism for accomplishing this object is shown in detail in Fig. 5 in which there is illustrated a fork-shaped lever pivoted at 90 on a fixed pivot mounted on one of the guide rails. This lever has a pair of arms 91 and 92 projecting from one side of the pivot and a curved arm 93 projecting from the opposite side of the pivot. Each of the counterweights has pivoted to lugs 95 depending from the lower end thereof an arm 96 adjustable between lock nuts 97 on a threaded stud 98. The free end of the arm has a laterally projecting end 99 adapted to engage one or the other of the fork arms 91 or 92 as hereinafter set forth. One of the door sections has projecting laterally from one face thereof a stud 100 adapted to be engaged by the curved arm 93 of the lever.

A relatively heavy spring 101 has one end 102 secured to the guide rail and the other end secured at 103 to the arm 93. In Figs. 4 and 5 the spring 101 is exerting a force tending to rotate the lever in a clockwise direction and since the lever engages the stud 100, this force tends to depress the door and assist in moving the door to completely closed position. When the door is to be opened and the control mechanism is operated to start the motor and lower the cable 60, permitting the counterweight to move downwardly, the end 99 of the arm 96 by reason of its engagement with the arm 92 of the lever will swing the lever in an anti-clockwise direction until the lever reaches the position shown in dotted lines in Fig. 5. It should be noted that in this position of the lever, a line passing through the points 102 and 103 is disposed to the left of the pivot 90 and the spring 101, therefore, tends to hold the lever in the dotted line position in which it engages an adjustable stop 104. In this position of the lever, the arm 91 is disposed in the path of movement of the end 99 of the arm 96 so that when the counterweight is again raised to permit the door to close, the lever will be

125
130

swung in a clockwise direction about its pivot 90 and after the lever has been swung to a sufficient extent for the spring 101 to be disposed in a line to the right of the pivot 90, the spring will exert a downward pull against the stud 100, thus assisting in closing the door.

Fig. 9 illustrates a slightly different form of lever. In this figure the lever is pivoted 10 at 90 and has a fork-shaped portion 105 and an arm 106 disposed on the opposite side of the pivot from the fork-shaped portion and at an angle thereto. The spring 101 is connected to an arm 106 of the lever at 107. The 15 stud 100 on the door is positioned between the fork tines or legs 108 and 109 of the portion 105 of the lever when the door is closed.

On opening the door, the stud 100 will engage the fork leg 108 and swing the lever in 20 an anti-clockwise direction to a position in which the spring 101 will act on the opposite side of pivot 90 and hold the lever against stop 104. When the door closes stud 100 will engage leg 109 and when the lever has moved 25 in a clockwise direction a slight extent spring 101 will pull the lever down and assist in moving the door to closed position.

Circuit control devices for motor and door locks

In Fig. 3 circuits are illustrated for controlling the operation of the motor and the door locks which lock the doors in closed position. The elevator E is shown as disposed 35 opposite the floor levels B and C. The positive control main is shown at X and the return or negative side of the control main is shown at Y.

In order to start the motor in operation 40 and open the doors at the two floor levels B and C, a separate manually controlled switch, such as a push button self-holding switch, is provided for each floor level and it is necessary that both of these switches be closed before the motor can be started in operation. Such switches are shown at floor levels B and 45 C and are indicated as switches 110 and 111, but these switches may be remotely located on a dispatcher's switch board, if preferred. Each switch is surrounded by a solenoid or 50 magnet winding 112, the winding of the switch 110 being connected at 113 to the positive control main X. The opposite end of the solenoid winding of switch 110 is connected to a switch contact 114 which is adapted to 55 engage a contact 115 when the switch is closed. Contact 115 is connected by a wire 116 to a contact 117 adapted to slidably engage and close contact with a contact cam 118 carried by the elevator car. The cam 118 is 60 connected by a wire 120 to a cam 121 also carried by the elevator car but disposed at the floor level C. Manually operable switches 123 65 and 124 are interposed in the wire 120 by

means of which the circuit through this wire can be broken.

The magnet or solenoid winding 125 for the switch 111 is connected at one end to an intermediate positive control 119 and at its 70 opposite end to a contact 126 to engage contact 127 connected by a wire 128 to a contact 129 which in turn is adapted to slidably engage the contact cam 121.

An electrically controlled spring actuated 75 door lock 130 is provided for each door and is normally actuated to locking position by a spring 131. The lock 130 is, however, surrounded by a magnet or solenoid winding 133 connected at 134 to the intermediate positive 80 control main 119 and connected at its opposite end to a contact 135 engageable with a cam contact 136 carried by the car E. All of the door locks are connected and controlled in the same manner.

The cam contacts 136 carried by the elevator car are connected by wires 140 and 141 to a wire 142 connected by wires 143 and 144 to contacts 145 and 146. The contact 145 is adapted for engagement with the contact 150 which is connected by a wire 151 to a magnet or solenoid winding 152, the other end of the winding being connected by a wire 153 to an arcuate contact 154. The magnet winding 152 is adapted to actuate a switch member 156 which forms the core of the magnet and has at one end thereof a contact 157 adapted to engage the contact 146 and at its opposite end a contact 158 adapted to engage a contact 159. Contact 159 is connected by a wire 160 to a contact 161 which in turn is connected by a wire 162 to one side of the motor 84.

The contact 157 is connected by a wire 170 to a magnet or solenoid winding 171 of a switch 172 having the contact 150 at one end thereof and a contact 173 at the opposite end thereof adapted to engage the contact 161. The other end of the magnet or solenoid winding 171 is connected by a wire 175 to an arcuate contact 176, the arcuate contacts 154 and 176 being concentric but having different radii.

A switch blade 180 is mounted on the shaft 75 and is adapted to engage one or the other of the arcuate contacts 154 or 176. The blade 180 is connected by a wire 181 to the negative side of the power main.

Contacts 158 and 173 of the switches 156 and 172 are connected by a wire 183 which in turn is connected to the negative side of the power main.

In order to permit the operators on the two floors being served by the elevator to signal each other when they are ready to depress the control buttons 110 and 111 and open the doors, signal bells are provided at each floor landing. In Fig. 3 there is shown a battery Z connected by a wire 190 to switch terminals 191 and 192 disposed at different floor levels.

The elevator is provided with contacts 194, 195, 196 and 197 adapted to engage and contact with contacts 198, 199, 200 and 201 disposed in the hatchway, when the elevator is disposed opposite the floor levels served thereby.

Contacts 198 and 200 are connected by wires 205 and 206 to signal bells 208 and 209, the bells being also connected by wires 210 and 211 to a wire 212 which is connected to the other side of the battery. The elevator contacts 194 and 197 are connected by a wire 215 and contacts 195 and 196 are connected by a wire 216.

When the switch 191 is closed, the circuit is completed from the battery through wire 190, switch 191, contacts 199, 195, wire 216, contacts 196, 200, bell 208, wire 211 and wire 212 back to the battery. Thus, when the switch on floor level B, for instance, is closed, the bell on floor level C will ring.

Similarly, when switch 192 is closed, the circuit will be completed from the battery through wire 190, switch 192, contacts 201, 25 197, wire 215, contacts 194, 198, bell 209, wire 210 and wire 212 back to the battery.

It will be seen, therefore, that in order for the signal bells to operate, it is necessary that a car be positioned opposite the floor levels on which the bells are located and when this condition is met, the closing of the switch or push button on one of the floors served by the elevator will signal the operator at the other floor, thus indicating that the operators are ready to close the self-holding switches 110 and 111 and set in operation the door operating mechanism.

Operation of door control circuits

40 After the operators of the two floors have signalled that they are ready to close the switches 110 and 111, these switches will be closed and will be held in closed position by the magnet coils 112 and 125 as long as the 45 motor circuit is closed. After the motor has rotated the arm 61 and the switch blade 180 through 180°, the circuit will be automatically opened and the switches 110 and 111 will be released from the action of the magnet coils.

When the switches are closed, a circuit will be completed from the positive main X through wire 112, contacts 114 and 115, wire 116, contacts 117 and 118, wire 120 contacts 55 121 and 129, wire 128, contacts 127 and 126, wire 125 to the wire 119. The circuit will also pass from wire 119 through the magnet coils 133 of the door locks, releasing the door locking means and from these coils through 60 contacts 135 and 136, wires 140 and 141, wires 142 and 144, contacts 146 and 157, wire 170, magnet or solenoid winding 171, wire 175, arcuate contact 176, switch blade 180 and wire 181 to the negative side Y of the power 65 main. The energizing of the coil 171 will

close the contacts 173 and 161, thus completing the motor circuit of motor 84 since the other side of the motor is connected to the positive side of the power main and the closing of the contacts 173 and 161 will connect the opposite side of the motor to the negative side of the power main. When the crank 61 and blade 180 have been rotated through 180°, the circuit through the blade and contact 176 will be broken and the motor will stop.

Assuming that the crank 61 has been rotated to the position shown in Fig. 1 by the operation just described and the doors have been opened if it is desired to close the doors and the blade is in engagement with the arcuate contact 154, the closing of the switches 110 and 111 will cause the circuit to pass from the wire 142 through wire 143, contacts 145 and 150, wire 151, magnet coil 152, arcuate contact 154 and blade 180 to the negative side Y of the power main. The energizing of the magnet coil 152 will cause the contacts 158 and 159 to close, thus again closing the motor circuit or connecting the negative side of the motor to the negative side of the power main.

It should be noted that the closing of the contacts 158 and 159 opens the contacts 146 and 157 and the closing of the contacts 173 and 161 opens the contacts 145 and 150. Thus, only one of the circuits can be in operation at a time.

From the foregoing description it will be seen that simple and practical control circuits have been provided for controlling the motor and door operating mechanism and that the closing of the switches by the operators at the two floor levels served by the elevator will result in the operation of the motor to open or close the doors disposed at the floor levels. It should be understood that the invention is not limited to the particular circuits illustrated and those shown have been illustrated merely for the purpose of showing one way in which the operation can be carried out.

It will be evident from the foregoing description that the motor is operated in one direction only and that the operation of the motor to move the crank through 180° in one direction will cause the counterweights of the open doors to be raised and the operation of the crank through the remaining 180° of its revolution will cause the counterweight control cable to be lowered, thus lowering the counterweights of the unlocked doors and causing the doors to open.

In case of fire the fusible links 52 and 58 melt and release the open doors from the action of the counterweights and permit them to close.

Although certain specific embodiments of the invention have been particularly shown and described, it will be understood that the

invention is capable of modification and that changes in the construction and in the arrangement of the various cooperating parts may be made without departing from the spirit or scope of the invention, as expressed in the following claims.

What we claim is:

1. Door closure mechanism comprising a door, a counterweight connected to open said door, a motor, a crank rotatable by said motor and connections so constructed and arranged that the rotation of said crank through a portion of a revolution will raise said counterweight and the rotation of the crank through the rest of the revolution will lower the counterweight.

2. Door closure mechanism comprising a door, a counterweight connected to open said door, a motor, a crank rotatable by said motor and connections so constructed and arranged that the rotation of said crank through a portion of a revolution will raise said counterweight and permit the door to close and the rotation of the crank through the rest of the revolution will lower the counterweight and cause the door to be opened thereby.

3. In combination, a plurality of door openings, a door for each opening, a counterweight connected to each door and adapted to open said door, a member having means adapted to engage and support said counterweights, said counterweights being movable relative to said means, and means connected to said member for lifting said member and said counterweights, thus permitting the doors to close.

4. In combination, a plurality of door openings, a door for each opening, a counterweight connected to each door and adapted to open said door, a cable having resilient means connected to said cable for lifting said counterweights, thus permitting the doors to close.

45 5. In combination, a plurality of door openings, a door for each opening, a counterweight connected to each door and adapted to open said door, a cable, resilient supports on said cable adapted to engage and support said counterweights, and means connected to said cable and adapted to raise and lower said cable and supports.

55 6. In combination, a plurality of vertically spaced door openings, a door for each opening movable to open and closed positions relative thereto, a lock for holding each door closed, a counterweight operatively connected to move each door to open position, a cable, means for raising and lowering said cable and vertically spaced supports on said cable engageable with said counterweights to lift said counterweights as the cable is raised.

65 7. In combination, a plurality of vertically spaced door openings, a door for each open-

ing movable to open and closed positions relative thereto, a lock for holding each door closed, a counterweight operatively connected to move each door to open position, a cable, means for raising and lowering said cable and vertically spaced, resilient supports on said cable engageable with said counterweights to lift said counterweights as the cable is raised.

8. In combination, a plurality of vertically spaced door openings, a door for each opening movable to open and closed positions relative thereto, a lock for holding each door closed, a counterweight operatively connected to move each door to open position, means for raising and lowering said counterweights, and means controlled by each counterweight for moving the door connected thereto to closed position.

9. In combination, a door movable to open and closed positions, door operating mechanism for said door including a counterweight for opening the door, and means controlled by the counterweight and engageable with the door as the door approaches closed position for moving the door into closed position.

10. In combination, a door movable to open and closed positions, door operating mechanism for said door including a counterweight for opening the door, and pivoted means engageable with the door only as the door approaches closed position for moving the door into closed position.

11. In combination, a door movable to open and closed positions, door operating mechanism for said door including a counterweight for opening the door, and means pivoted on a fixed support and controlled by the counterweight and engageable with the door as the door approaches closed position for moving the door into closed position.

12. In combination, a door movable to open and closed positions, door operating mechanism for said door including a counterweight for opening the door, and spring actuated means engageable with the door only as the door approaches closed position for moving the door into closed position.

13. In combination, a plurality of hatchway doors disposed at different floor levels and movable to open and closed positions, a counterweight connected to each door and adapted to move the door to open position, a crank, a cable connected to said crank, means to rotate said crank, and spaced members carried by said cable and adapted to support said counterweights and permit the doors to close.

14. In combination, a plurality of hatchway doors disposed at different floor levels and movable to open and closed positions, a counterweight connected to each door and adapted to move the door to open position, a crank, a cable connected to said crank, means to rotate said crank, and spaced members car-

ried by said cable and adapted to support said counterweights and permit the doors to close, said cable, crank and counterweight supports being so relatively constructed and arranged that the counterweights will be raised, permitting the doors to close, in one position of the crank and will be lowered, thus opening the doors in another position of the crank.

15. In combination, a plurality of hatchway doors disposed at different floor levels, an elevator having a plurality of decks, door operating means including a motor, control mechanism including manually operable switches for the different floor levels, and circuits so constructed and arranged that the motor circuit will not be closed unless the switches for the levels served by the elevator decks are closed.

20. In combination, a plurality of hatchway doors disposed at different floor levels, an elevator having a plurality of decks, electrically controlled locks for locking the doors, door operating means including a motor, control mechanism for said operating means, said control mechanism including manually operable switches for the different floor levels, and circuits so constructed and arranged that the doors opposite the elevator decks will be unlocked and the motor circuit will be closed when the switches for said levels are closed.

25. In combination, a hatchway door movable to open and closed positions, an electrically controlled lock for the door, door operating mechanism including a motor and circuits including the lock and motor and so constructed and arranged that the closing of the circuit will release the lock and operate the motor and a manually operable switch controlled when closed by the motor circuit for closing the motor and lock circuits.

30. In combination, a hatchway door movable to open and closed positions, an elevator car, an electrically controlled lock for the door, door operating mechanism including a motor and circuits including the lock and motor and so constructed and arranged that the closing of the circuit will release the lock and operate the motor, said circuits including a switch having a contact on the car and adapted to be closed when the car is disposed at the floor level and a manually operable switch controlled when closed by the motor circuit for closing the motor and lock circuits.

35. In combination, a hatchway door movable to open and closed positions, an elevator car, an electrically controlled lock for the door, door operating mechanism including a motor and circuits including the lock and motor and so constructed and arranged that the closing of the circuit will release the lock and operate the motor, said circuits including a switch having a contact on the car

and adapted to be closed when the car is disposed at the floor level and a manually operable switch controlled when closed by the motor circuit for closing the motor and lock circuits.

40. Door closure mechanism comprising a door, a counterweight connected to open said door, a motor, a crank shaft driven by the motor, a crank carried by said crank shaft and rotatable by said motor and connections so constructed and arranged that the rotation of said crank through a portion of a revolution will raise said counterweight and the rotation of the crank through the rest of the revolution will lower the counterweight, and counterweighting means operatively connected to said crank shaft for assisting the motor in rotating the crank in one direction and lifting the door counterweight.

45. In combination, a vertically moving door, motor operated mechanism including a crank shaft and a crank for controlling the opening and closing of the door, manually controlled means including a switch for setting the motor operated mechanism in operation, and switch means controlled by the crank shaft for discontinuing the operation of said mechanism when the door has been opened or closed.

50. Door closure mechanism comprising a door, motor operated mechanism including a crank and a switch rotatable with said crank for controlling the motor circuit and effecting the opening and closing of the door, said mechanism being constructed and arranged to effect the opening of the door during the movement of the crank through a portion of its revolution and to effect the closing of the door as the crank moves through the rest of its revolution.

55. Door closure mechanism comprising a door, motor operated mechanism including a crank and a switch rotatable with said crank for controlling the motor circuit and effecting the opening and closing of the door, said mechanism being constructed and arranged to effect the opening of the door during the movement of the crank through a portion of its revolution and to effect the closing of the door as the crank moves through the rest of its revolution, said switch being constructed and arranged to open the motor circuit when the motor has moved the crank through the door opening or door closing portion of its revolution.

60. Door closure mechanism comprising a door, a motor, a crank rotatable by the motor, operative connections controlled by the crank and so constructed and arranged that rotation of the crank through one-half of a revolution will effect the opening of the door and rotation of the crank through one-half of a revolution will effect the closing of the door, and means for opening the motor circuit when the crank completes each half revolution.

25. Door closure mechanism comprising a door, motor operated mechanism including a crank for effecting the opening and closing of the door, said mechanism being constructed and arranged to effect the opening of the door during the movement of the crank through 180° and to effect the closing of the door during the movement of the crank through 180° , and means for opening the motor circuit when the crank completes each half revolution.
- 10 26. Door closure mechanism comprising a door, a motor, motor operated mechanism including a crank for effecting the opening and closing of the door, said mechanism being constructed and arranged to effect the opening of the door during the movement of the crank through a portion of its revolution and to effect the closing of the door as the crank moves through a portion of its revolution, and means 15 for opening the motor circuit when the crank has effected the opening or the closing of the door.
- 20 27. Door closure mechanism comprising a door movable vertically to open and closed positions, means operatively connected to both side edges of the door for lifting said door vertically to open position, and control means for said lifting means movable through one-half the distance of movement of the door from closed to wide open position, for effecting the opening and closing of said door.
- 25 28. Door closure mechanism comprising a door movable vertically to open and closed positions, single lifting means operatively connected to both side edges of the door for moving the door to open position, said operative connections being so constructed and arranged that the lifting means in effecting the movement of the door from closed to open position moves one-half the distance of movement of the door, and means for raising and lowering said lifting means.
- 30 29. Door closure mechanism comprising a door movable vertically and laterally to open and closed positions, single lifting means operatively connected to the door for moving the door to open position, said operative connections being so constructed and arranged that the lifting means in effecting the movement of the door from closed to open position moves one-half the distance of movement of the door, and means including a crank for raising and lowering said lifting means.
- 35 30. Door closure mechanism comprising a door movable vertically and laterally to open and closed positions, single lifting means operatively connected to the door for moving the door to open position, said operative connections being so constructed and arranged that the lifting means in effecting the movement of the door from closed to open position moves one-half the distance of movement of the door, and means including a crank for raising and lowering said lifting means, said

crank being movable through one-half a revolution to raise or lower said lifting means.

31. Door closure mechanism comprising a plurality of doors movable vertically to open and closed positions, lifting mechanism for effecting the vertical movement of the doors to closed position, said mechanism including a driven member, and operative connections between said driven member and each of said doors, said connections including means providing for variations between the amount of travel of the driven member and the doors operated thereby.

32. In combination, a door, closing mechanism therefor, operative connections between said closing mechanism and said door, said connections including resilient means to vary the length of said operative connections, and spring actuated means operable only as the door approaches closed position for moving the door into fully closed position.

33. In combination, a door, closing mechanism therefor, operative connections between said closing mechanism and said door, said connections including resilient means to vary the length of said operative connections, and spring actuated means operable only as the door approaches closed position and engageable with the door for moving the door into fully closed position.

34. In combination, a door, closing mechanism therefor, operative connections between said closing mechanism and said door, and spring actuated means operable only as the door approaches closed position for moving the door into fully closed position.

35. In combination, a plurality of floor levels having a hatchway door opening at each floor level, a hatchway door disposed at each floor level and located out of the hatchway, each door being movable vertically and laterally to open position, lifting means connected to each door, and means extending through the floors at said floor levels for controlling said lifting means.

36. In combination, a plurality of floor levels having a hatchway door opening at each floor level, a hatchway door disposed at each floor level and located out of the hatchway, each door being movable vertically and laterally to open position, and lifting means connected to each door, each lifting means being movable through one-half the distance of movement of the door moved thereby from closed to open position in effecting the opening of the door.

37. In combination, a plurality of floor levels having a hatchway door opening at each floor level, a hatchway door disposed at each floor level and located out of the hatchway, each door being movable vertically and laterally to open position, lifting means connected to each door, and means extending through the floors at said floor levels for controlling said lifting means, each lifting means being

- movable through one-half the distance of movement of the door moved thereby from closed to open position in effecting the opening of the door.
38. In combination, a plurality of floor levels having a hatchway door opening at each floor level, a hatchway door disposed at each floor level and located out of the hatchway, each door being movable vertically and laterally to open position, lifting means connected to each door, and single means extending through the floors at said floor levels for controlling said lifting means. 5 70
39. In combination, a plurality of floor levels having a hatchway door opening at each floor level, a hatchway door disposed at each floor level and located out of the hatchway, each door being movable vertically and laterally to open position to the full height of the door opening lifting means connected to each door, and means extending through the floors at said floor levels for controlling said lifting means. 10 75
40. In combination, a plurality of door openings, a door for each opening, counterbalancing means connected to each door for opening the door, and a member having means engaging said counterbalancing means and movable to permit said counterbalancing means to open the doors. 15 80
41. In combination, a plurality of door openings, a door for each opening, counterbalancing means connected to each door for opening the door, and a cable having abutments thereon engaging said counterbalancing means and movable to permit said counterbalancing means to open the doors. 20 85
42. In combination, a plurality of door openings, a door for each opening, a counterbalancing means connected to each door for moving the door, and a member having means engaging and controlling the operation of said counterbalancing means to move the doors said counterbalancing means being movable relative to said means. 25 90
43. In combination, a plurality of door openings, a door for each opening, counterbalancing means connected to each door for moving the door, and a member passing through said counterbalancing means and having means movable with said member and engaging and controlling the operation of said counterbalancing means to move the doors. 30 95
44. In combination, a plurality of door openings, a door for each opening, a counterweight connected to each door for moving the door, and a member passing through the center of gravity of said counterweight and having means movable with said member and engaging and controlling the operation of said counterweight to move the doors. 35 100
45. In combination, a plurality of hatchway doors vertically movable to open and closed positions, a counterweight for each 40 105
- door, sheaves carried thereby, flexible means connected to the sides of each door and passing around said sheaves, and lifting means for said counterweights passing through the counterweights and between said sheaves. 110
46. In combination, a plurality of hatchway doors vertically movable to open and closed positions, a counterweight operatively connected to each door, and lifting means for said counterweights passing through the counterweights. 45 115
47. In combination, a plurality of door openings, a door for each opening, counterbalancing means connected to each door for opening the door, and a member having means engaging with and controlling the operation of said counterbalancing means to move the door. 50 120
48. In combination, a plurality of door openings, a door for each opening, a counterbalancing means connected to each door for opening the door, and a member having means engaging with and selectively controlling the operation of said counterbalancing means to move the door. 55 125
49. Door operating mechanism comprising a door movable to open and closed positions, a motor, a crank rotatable by said motor, a tension member operatively connecting said crank and said door, and a weight rotatable in unison with said crank for counteracting the weight of said tension member. 60 130
- In witness whereof, I have hereunto set my hand this 27th day of June, 1927.
